(57) **CLAIM**

The ornamental design for a multipurpose transformable crutch chair as shown and described.

DESCRIPTION

Multipurpose transformable crutch chair

1.1 is a front view of a multipurpose transformable crutch chair in a configuration of normal crutch, showing the new design;

1.2 is a back view thereof;

1.3 is a left view thereof;

1.4 is a right view thereof;

1.5 is a top view thereof;

1.6 is a bottom view thereof;

1.7 is a front, right perspective view thereof;

1.8 is a back, right perspective view thereof;

1.9 is a front view of the multipurpose transformable crutch chair in a chair configuration;

1.10 is a back view thereof;

1.11 is a left view thereof;

1.12 is a right view thereof;

1.13 is a top view thereof;

1.14 is a bottom view thereof;

1.15 is a back, right perspective view thereof;

1.16 is a front, right perspective view thereof;

1.17 is a front view of the multipurpose transformable crutch chair in a configuration of long crutch;

1.18 is a back view thereof;

1.19 is a left view thereof;

(Continued)

1.20 is a right view thereof;
1.21 is a top view thereof;
1.22 is a bottom view thereof;
1.23 is a front, left perspective view thereof;
1.24 is a front, right perspective view thereof;
1.25 is a front view of the multipurpose transformable crutch chair in a storage configuration;
1.26 is a back view thereof;
1.27 is a left view thereof;
1.28 is a right view thereof;
1.29 is a top view thereof;
1.30 is a bottom view thereof;
1.31 is a front, right perspective view thereof; and
1.32 is a back, right perspective view thereof.

The broken lines illustrate portions of the multipurpose transformable crutch chair that form no part of the claimed design.
